HANDBAG OR SIMILAR ARTICLE

Maurice A. Spector, New York, N. Y.

Application April 25, 1951, Serial No. 14,947

Term of patent 14 years

(Cl. D87—3)

To all whom it may concern:

Be it known that I, Maurice A. Spector, a citizen of the United States of America, residing in New York city, county of New York, and State of New York, have invented a new, original, and ornamental Design for a Handbag or Similar Article, of which the following is a specification, reference being had to the accompanying drawing, forming part thereof, wherein:

Figure 1 is a front perspective view of a handbag showing my new design.

Figure 2 is a front elevational view of the handbag shown in Figure 1, drawn on a smaller scale; and

Figure 3 is a side elevational view.

The rear of the handbag is substantially plain.

My design for a double-handled, frame closed handbag with side pockets is characterized by

the asymmetrical height of the outer walls of said side pockets together with the slide fastener closure across the top of the higher outer wall, all as shown.

I claim:

The ornamental design for a handbag or similar article, substantially as shown and described.

MAURICE A. SPECTOR.
